LUBRICANT PUMP

Ernest W. Davis, River Forest, Ill., assignor to
 Stewart-Warner Corporation, Chicago, Ill., a
 corporation of Virginia

Application September 11, 1943, Serial No. 501,934

3 Claims. (Cl. 222—255)

My invention relates to pumps for pumping lubricant, and more particularly to pumps for pumping very heavy lubricant, wherein the cohesive force of the lubricant is so strong that atmospheric pressure alone is incapable of projecting the lubricant through the relatively long and bending inlet passageways usually provided in pumps designed for handling lubricants of ordinary consistency.

The principal object of this invention is to provide a pump of the class described which will pump very heavy lubricant in an efficient manner, even when the lubricant to be pumped is abnormally cold. Other objects will appear as the description proceeds.

In the drawings—

Fig. 1 is an elevation in partial section showing the lubricant pump of this invention;

Fig. 2 is a central longitudinal section of the pumping elements and associated parts;

Fig. 3 is a transverse section on the line 3—3 in Fig. 2;

Fig. 4 illustrates the inoperative performance of an ordinary grease pump when used with lubricant having unusually high viscosity, such as that which can be handled successfully with the lubricant pump of this invention;

Fig. 5 illustrates one stage in the operation of the lubricant pump of this invention;

Fig. 6 illustrates the next succeeding stage of the operation;

Fig. 7 illustrates a further stage of the operation; and

Fig. 8 illustrates a more advanced stage of the operation.

Referring to Fig. 1, the lubricant pump of this invention employs a container 10 for holding lubricant. The container 10 is provided with a cover 12, which supports an air engine 14 for producing the reciprocating motion necessary for operating the working parts of the pumping mechanism which will be described hereinafter. The air engine 14 is of a general type well known to those skilled in the art, and detailed description is therefore unnecessary.

The air engine 14 is provided with the usual piston rod 16 (Fig. 2) to which is secured the pump piston rod 18, which extends downwardly into the stationary cylinder 20 where it is connected with the cylinder head 22 of the movable cylinder 24. The cylinder head 22 is provided with a number of perforations 26. The check valve 28 is movable coaxially with the connecting rod 18 between the cylinder head 22 and the cross pin 30. The downwardly extending por-

tions 32 are integral with the stationary cylinder 20 and provide supports for positioning the stationary piston 34, which is of a diameter that fits closely within the movable cylinder 24.

The booster pump cylinder 36 is provided with a discharge outlet 38, and is fitted with a lapped piston 40 which, upon upward movement of the piston rod 18, engages with the check valve 42. The booster pump cylinder 36 is threaded at its lower end for retaining the cap 44, which is provided with a valve seat 46, against which the check valve 42 is seated during downward movement of the piston rod 18.

The follower plate 50 (Fig. 1) is maintained in a horizontal position by the bushing 52, and is provided with turn screws 54, 56, by means of which the follower plate 50 is initially loosened from the bottom of the container 10, when the lubricant is nearly exhausted from the container 10.

The advantage of the construction used in this lubricant pump will be more apparent by comparing its operation with that of an ordinary pump designed for use with lubricants of ordinary consistency. The condition responsible for failure of such a pump is illustrated in Fig. 4, wherein the check valve 58 is moved to the position shown during the flow of ordinary lubricant into the cylinder 58 along the paths of travel indicated by the broken lines. Such a foot valve is entirely satisfactory for use with soft lubricant that is not too cold, but is not satisfactory for use with lubricant of the class that is commonly designated as fibrous lubricant, and especially when it is abnormally cold. Such fibrous lubricant 60, when used with the foot valve shown in Fig. 4, has a cohesive force so strong that atmospheric pressure can force it into the foot valve only to the position shown, which is insufficient to provide any pumping action.

Operation

Atmospheric pressure acting on heavy lubricant when used in the pump of this invention will force the lubricant inwardly, between the extending portions 32, 32, as shown in plan view in Fig. 3, and as shown in elevation in Fig. 5, so that downward movement of the movable cylinder 24 to the position shown in Fig. 6, will start to shave off segregated portions of lubricant 62, 62, which are forced upwardly into the movable cylinder 24 upon movement thereof to the position shown in Fig. 7, in which position the movable cylinder 24 surrounds the piston 34. This results in the discharge of lubricant up-

wardly from the movable cylinder 24, past the check valve 28, and into the stationary cylinder 20, as shown at the numeral 64. The following upward movement of the movable cylinder 24 to the position shown in Fig. 8 will then fill up the void space 66 in Fig. 7, and will open a void space 68 (Fig. 8) which will be partly filled with lubricant 60 by the time the movable cylinder reaches its extreme uppermost position, as shown in Fig. 5. The movable cylinder 24, in moving from the position shown in Fig. 8 to the position shown in Fig. 5, will displace lubricant upwardly in the stationary cylinder 20, as will be readily understood.

During upward movement of the movable cylinder 24, the booster pump piston 40 is also moved upwardly, thereby expelling lubricant through the discharge outlet 38 and simultaneously providing space below the piston 40 for the inflow of lubricant from the stationary cylinder 20, past the check valve 48. The following downward movement of the piston rod 16 into the booster pump cylinder 36 causes displacement of lubricant which closes the check valve 48 and causes lubricant to be discharged through the discharge outlet 38. Thus the booster pump discharges lubricant on both the up stroke and down stroke of the piston rod 16.

Owing to the difference of consistency of different lubricants, and the difference of consistency in the same lubricant at different temperatures, it is impossible to predict the exact amount of lubricant that will be shaved off during downward movement of the movable cylinder 24. In case the amount shaved off is less than the normal displacement in the booster pump cylinder 36, then the resulting void spaces in the lubricant will be closed in the booster pump cylinder 36, and the amount of lubricant discharged through the discharge outlet 38 will be somewhat less than normal. On the other hand, if the amount of lubricant shaved off is greater than the normal displacement in the booster pump cylinder 36, then the excess lubricant will escape downwardly past the movable cylinder 24, which fits loosely within the stationary cylinder 20 in order to provide this action.

If the piston 40 and check valve 44 are removed, the pump will then function as a low pressure pump, which construction may be of utility under some conditions of service, such as filling hand guns, or applying lubricant in cavities of ample size where little pressure is required.

While the pump of this invention is described as a lubricant pump, suitable for use in handling heavy lubricants, its suitability for pumping plastic substances other than lubricants is quite obvious.

I claim:

1. In a three stage lubricant pump having, a container for holding a main body of lubricant; a movable cylinder within said container; a piston for said cylinder, said piston being positioned within the space normally occupied by said main body of lubricant; means for producing reciprocating movement of said movable cylinder relative to said piston and relative to said main body of lubricant, said reciprocating movement extending between a position in which said movable cylinder is removed from said piston and a position in which said movable cylinder surrounds said piston, whereby movement of said movable cylinder through said main body of lubricant in a direction towards said piston, will first shave off a segregated quantity of said lu-

bricant, and whereby continued movement of said movable cylinder to a position surrounding said piston, will then displace said segregated lubricant longitudinally within said movable cylinder; secondary pumping means connected to said movable cylinder for receiving and re-pumping the lubricant segregated and displaced thereby; and a booster pump for applying high pressure to said re-pumped lubricant, said booster pump being actuated by said reciprocating means, and said booster pump receiving lubricant from said secondary pumping means.

2. In a lubricant pump, having a container for holding a main body of lubricant; a stationary cylinder extending downwardly in said container and terminating some distance from the bottom of said container; a stationary piston positioned in axial alignment with said stationary cylinder at an elevation below the lower end of said stationary cylinder; a movable cylinder slidable inside of said stationary cylinder to a position above said piston and to a position surrounding said piston; means for restricting downward flow of lubricant from said stationary cylinder and past said movable cylinder; and means for reciprocating said movable cylinder between a position in which said movable cylinder is removed from said piston and a position in which said movable cylinder surrounds said piston, whereby movement of said movable cylinder through said main body of lubricant in a direction towards said piston, will first shave off a segregated quantity of said lubricant, and whereby continued movement of said movable cylinder to a position surrounding said piston, will then displace said segregated lubricant upwardly in said movable cylinder, thereby discharging lubricant from said movable cylinder into said stationary cylinder, and whereby succeeding upward movement of said movable cylinder will then displace said discharged lubricant upwardly within said stationary cylinder.

3. In a lubricant pump having, a container for holding lubricant; a stationary cylinder extending downwardly in said container and terminating some distance from the bottom thereof; a plurality of extending portions connected with said stationary cylinder and extending downwardly in said container; a stationary piston supported by said extending portions; a movable cylinder coaxial with said stationary cylinder and slidable therein to an upper position in which said piston is exposed to said lubricant, and to a lower position in which said movable cylinder surrounds said piston; means for preventing downward flow of lubricant through said movable cylinder; and means for reciprocating said movable cylinder between said upper position and said lower position, whereby initial downward movement of said movable cylinder through said lubricant will first shave off and segregate those portions of said lubricant which protrude inwardly between said extending portions, and whereby continued downward movement of said movable cylinder to said lower position, will displace said segregated portions of lubricant upwardly in said movable cylinder, and whereby the following upward movement of said movable cylinder within said stationary cylinder, will then produce a piston effect in said stationary cylinder for further displacement of said lubricant upwardly in said stationary cylinder.
